[57] ABSTRACT

The tool is used to slip a flat flange-containing cover strip into two parallel facing grooves. The cover is passed through the tool which has a flared tubular body. The flat shape of the cover strip is converted into a curved configuration so that the flanges of the cover will slide into the parallel grooves.

INSTALLATION TOOL

CROSS REFERENCE TO RELATED APPLICATION

The tool is used to insert the cover strip into the groove structure set forth in copending commonly assigned U. S. application Ser. No. 153,508, filed June 16, 1971, entitled "Joint Construction for Ceiling Panels," filed in the name of John R. Davey et al.

BACKGROUND OF THE INVENTION

1. Field of the Invention

The invention is directed to an installation tool and, more particularly, to a tool for installing a component part of a ceiling system.

2. Description of the Prior Art

In the past, the cover structures such as shown in the above-mentioned copending U. S. application were placed into parallel facing groove structures by inserting the one edge of the cover in one groove and then bending the body of the cover so that the flange on the opposite side of the cover would slide into the opposite groove. On some occasions, an individual would pinch the two flange edges of the cover together to bow the normally flat center portion of the cover and then insert the flanges of the cover into the parallel grooves. The releasing of the pressure which is causing the center portion of the cover to be bowed would permit the two flanges to slide into the parallel grooves.

To date, no tool has yet been provided in the art for rapidly slipping an element into two parallel groove structures wherein the element must be squeezed together to facilitate the placing of flanges on the element into the parallel groove structures.

SUMMARY OF THE INVENTION

The tool used for installing a flanged cover strip into two parallel grooves has a tubular body configuration. A handle is connected to the body to assist in the movement of the tool body. The inlet end of the tool has an oval configuration which is sized to approximately the relaxed-state width of the cover strip. The oval configuration gradually changes to a round configuration at the exit end of the tool, said round configuration being about equal in width to the spacing between the openings of the two parallel grooves. The tool bends the normally flat section of the cover strip into an arcuate configuration so that the flange structures of the cover strip can be slid into two parallel grooves which are normally placed in a ceiling board on either side of the region through which staples are passed to fasten the ceiling board in position.

BRIEF DESCRIPTION OF THE DRAWING

FIG. I is a top view of the tool;

FIG. II is a side view of the tool;

FIG. III is an end view of the tool with the cover strip inserted therein; and

FIG. IV is an end view of a ceiling board with the cover strip inserted therein and an end of the cover strip inserted into the tool.

DESCRIPTION OF THE PREFERRED EMBODIMENT

Referring now to FIG. I and FIG. II, there is shown the general construction of the installation tool herein. A handle 2 is provided to assist the user in grasping the instrument and for moving it along the cover strip

which is the same in construction as that shown as element 15 in the above-mentioned copending application. The main body 4 of the tool is a tubular structure. The inlet end 6 of the body, that is, the end that the cover strip is inserted into, is generally oval in cross-section. The oval cross-section gradually changes to a round configuration about the middle and towards the end of the tool body. The back upper side 8 of the tubular body is cut away, and the tool is usually used with the side 8 being run parallel to the surface into which the cover strip is to be inserted. This permits the tool to be held in the manner shown in FIG. II wherein the entrance or inlet opening 6 is sloped away from the area into which the strip is to be inserted. This will facilitate the handling of the strip and tool wherein the strip is fed into the entrance of the tool, compressed in its width dimension, and exits from the tool in close proximity to the area into which it is to be mounted.

Referring now to FIG. III, the round configuration 10 is generally the configuration of the tool from its mid-region to its exit opening. While it is true that a portion of the tool is cut away at 8 so that the exit end of the tool is not a true circle, the tool functions as if the full circular configuration were there and it holds the cover strip in its compressed state. As shown in FIG. III, the normally flat area 12 of the cover strip is bowed into a compressed state. The diameter of the circular section 10 is about equal to the distance between the openings of the two parallel facing grooves into which the strip is to be placed. The inlet opening 6 of the tool has an oval configuration which is in width at its major axis about equal to that of the strip in its unstressed or flat state. Consequently, as the strip is moved from the inlet opening 6 to the cross-sectional configuration 10, the shape of the strip changes from the cross-sectional shape shown at inlet opening 6 to the shape shown generally by the line 14.

Referring now to FIG. IV, it may be possible to see a little better how the tool operates. A ceiling board 16 is provided with a region 18 into which staples are driven. This could be any type of structure wherein there is a region which it is desired to conceal. On either side of the surface 18 there is provided two generally facing parallel grooves 20. These grooves are provided to receive the flanges on the cover strip which conceals the region 18. The cover strip generally has the relaxed unbowed configuration which is shown by the end 21 of the strip. Here the strip has its unbowed center region 22 and the two flanges 24 which are inserted into the grooves 20 to hold the strip in place. The installation tool tubular body 4 is generally shown in FIG. IV. The exit diameter of the tool must be about equal to the width between point 26 and point 28, which are the openings of the two parallel grooves. In order to readily insert the cover strip into the grooves, the ends of the flanges must be forced together so that the distance from the two ends of the flanges is less than the distance between points 26 and 28. When this condition exists, the ends of the flanges 24 can then slip down past the points 26 and 28 and then snap into the grooves 20. It is the tool 4 which compresses the cover strip so that the flanges are in such a condition as to get past points 26 and 28. The natural resiliency of the strip causes it to resume its normal flat condition after it has exited a short distance from the tool.

With the tool above-described and utilized in the manner above-described, it is possible for the ordinary

production worker to take the ceiling joint and cover strip structure as shown in the above-mentioned co-pending application and to rapidly install it in position in a mobile home structure or other similar type structure. The cover strip can be rapidly installed in position and can be installed in place with the minimum stresses being placed on the board structure. The board structure, generally being made of a fiberboard product, would be susceptible to damage should excessive forces be used to insert the cover strip in position. The tool herein affords a rapid and easy technique for getting the cover strip inserted into the parallel groove structures of a conventional ceiling board.

What is claimed is:

1. An installation tool for inserting a generally flat cover strip, with flanges thereon, into two parallel, generally facing, groove structures to provide an assembled unit wherein the generally flat cover strip is held in position by having its flanges inserted into the parallel grooves, the said tool being composed of a general body portion, and a handle attached thereto to permit manipulation of the body portion of the tool, said body portion of the tool having an inlet opening which is generally oval in configuration and an exit opening which is generally circular in configuration, said oval configuration having a major axis which is about equal to the width of the cover strip in its unstressed state, said round exit opening of the tool having a size which is much less than the width of the unstressed cover strip and about the distance between the openings of the two parallel grooves so that the cover strip is compressed to permit its flanges to slide into the parallel grooves, and said interior of said body portion being of a continuous

wall tubular construction without any recesses therein.

2. The installation tool of claim 1 wherein a portion of the tool adjacent the exit opening is partly cut away so as to permit the tool body portion to be inclined slightly relative to the plane of the surface containing the two parallel grooves.

3. The installation tool of claim 2 wherein the longitudinal axis of the handle is inclined at an angle to the longitudinal axis of the body portion.

10 4. An installation tool for inserting a generally flat cover strip, with flanges thereon, into two parallel, generally facing, groove structures to provide an assembled unit, said tool having a body portion having an oval inlet opening and a circular exit opening, said body portion being of tubular construction with a continuous interior wall without any recesses therein, said inlet opening has a major axis which is about equal to the width of the cover strip in its unstressed state, said circular exit opening having a size which is much less than the width of the unstressed cover strip and about the size of the distance between the openings of the two parallel groove structures.

20 5. The installation tool of claim 4 wherein the tool is provided with a handle which is slightly inclined relative to a line perpendicular to the axis of the body portion.

25 6. The installation tool of claim 5 wherein a portion of the body portion adjacent the exit opening is partly cut away so as to permit the tool body portion to be inclined slightly relative to the plane of the surface containing the two parallel groove structures.
